Thomas Connally
ATTORNEY.

UNITED STATES PATENT OFFICE.

LOUIS BERNIER, OF FERNDALE, MICHIGAN.

AUTOMATIC SWITCH CONTROL.

Application filed April 9, 1928. Serial No. 288,570.

My invention relates to a new and useful improvement in an automatic switch control adapted for use on railroad tracks and has for its object the provision of a mechanical means whereby the operator of the vehicle travelling over the tracks may automatically, without leaving the vehicle and while the vehicle is still travelling, operate the switch.

10 It is another object of the invention to provide a device of this class whereby the operating mechanism, after being operated to throw the switch in one direction, is automatically set for operation to throw the 15 switch in the opposite direction.

Another object of the invention is the provision of a device of this kind which will be simple in structure, economical of manufacture, durable and highly efficient in use.

20 Other objects will appear hereinafter.

The invention consists in the combination and arrangement of parts hereinafter described and claimed.

25 The invention will be best understood by a reference to the accompanying drawings which form a part of this specification and in which,

Fig. 1 is a top plan view of the invention showing it installed.

30 Fig. 2 is a sectional view taken on line 2-2 of Fig. 1 with a fragment of a vehicle shown thereon.

Fig. 3 is a perspective view of the operating mechanism used in the invention.

35 The device may be used on railroad tracks extending beyond the limits of a city, or may be used on street car tracks laid in the streets of a city, and in the drawings I have illustrated the adaptation of the invention 40 to the rails 9 and 10 which are laid in a street. A branch track 11 is illustrated, in connection with which is used the swingably mounted rail or switch 12, the location of which will determine the direction of 45 travel of a vehicle after passing the same when travelling from left to right on the drawings. Mounted between the rails 9 and 10 in a housing 13 having the cover 14 provided with a slot 15. Formed in this housing is a compartment 16 having the elongated portion 17, which extends beyond the free end of the switch rail 12. Mounted on the base 18 of this housing are spaced supports 19 and 20, extending slidably through 55 which are the rods 21 and 22. Fixedly

mounted on the rods 21 and 22 is the bridge 23. Swingably mounted on the upper surface of the bridge 23 is the wedge-shaped actuating finger 24 carrying the wedge-shaped head 25 preferably formed integral therewith. Projecting upwardly from opposite sides of the bridge 23 are the studs or engagement members 26 and 27 which are adapted to engage opposite faces of the actuating finger 24, when the same is swung 60 on its pivot. Preferably formed integral with and projecting upwardly from the bridge 23 are the spaced lugs 28 and 29, between which engages one end of the rod 30 which is pivotally mounted on these lugs 29 65 and 28 and which engages in the notch 31 formed in the upper edge of the support 20. Pivotally connected at one end to the outer end of the rod 30 is the operating bar 32 which is pivotally connected, intermediate 70 its ends, at a flattened portion 33, on a support 34 positioned in the compartment 17. Connected pivotally at one end to the opposite end of the bar 32 is a link 35 which is pivotally connected, intermediate its ends to 75 a pair of spaced lugs 36 and 37 which project outwardly from and are secured to one face of the switch rail 12.

Mounted on the undersurface of the floor 38 of the vehicle is a bolster 39. A rod 40 is 80 projected through the floor 38 and through the bolster 39 so as to lie, when the vehicle is drawn over the tracks, in alignment with the slot 15. A spring 41 serves to normally retain the lower end of the rod 40 spaced 85 above the cover 14.

In operation, when the vehicle is being propelled over the rails 9 and 10 and the switch is approached, and it is desired to throw the switch to its other position, the 90 operator of the vehicle will, by pressing on the head 42 of the rod 40, force the rod 40 downwardly against the compression of the spring 41 so that the lower end of the rod 95 will engage in the slot 15, a collar 43 being fixedly mounted on this rod to engage the bolster 39 and limit the downward movement thereof. When the end of the rod 40 is in engagement with the slot 15 and the 100 vehicle is drawn past the operating mechanism so as to cross over the location of the bridge 23, the lower end of the rod 40 will engage one face of the finger 24. As shown in full lines in Fig. 1 and Fig. 3, this finger 105 is in engagement with the stud 27, and in 110

order to permit the rod 40 to pass beyond the same, the rod engaging the inclined face of the finger will force the bridge to move toward the left, thus rocking the bar 32 and moving it into the position shown in dotted lines in Fig. 1, thus effecting a movement of the switch rails 12 into the position shown in dotted lines in Fig. 1. In this manner the switch is thrown. As the end of the slot 15 is approached, the end of the rod 40 will engage the inclined surface so that it will move out of engagement with the slot 15 without striking any abrupt shoulder on the cover 14.

15 As the pin passes the wedge-shaped head 25, the finger 24 will be rocked on its pivot into the position shown in dotted lines in Fig. 1 so that the finger 24 will be moved into engagement with the stud 26. In this 20 position a succeeding vehicle desiring to travel in the same direction as the preceding vehicle would not effect any operation of the switch, but one desiring to travel in a direction determined by the throwing of the 25 switch into the position shown in full lines in Fig. 1 would press the rod 40 downwardly so as to operate the switch. The opposite face of the finger 24 would in this case be engaged and an opposite movement of the 30 bridge 23 effected with a resultant rocking of the actuating finger 24, on its pivot, to prepare it for the next operation, so that the switch may again be thrown into its prior position.

35 It will be noted that in the switch itself there is an absence of springs. In this manner I have provided a mechanically operated device whereby the operator of the vehicle may automatically, while the vehicle is 40 travelling, throw a switch which is to be approached and prepare, at the same time, the actuating mechanism for operating the switch in the opposite direction by a succeeding 45 operation.

45 The simplicity of the device is believed evident, as well as its economical structure.

While I have illustrated and described the preferred form of my invention I do not wish to limit myself to the precise details of 50 structure shown, but desire to avail myself of such variations and modifications as come within the scope of the appended claims.

Having thus described my invention what I claim as new and desire to secure by Letters Patent is:

1. In a switch control of the class described, adapted for use on a track having a movable switch rail, comprising: a rockable bar; means for connecting one end of said 60 bar to said switch rail; a movable supporting member; means for connecting the opposite end of said bar to said movable supporting member; an engagement member rockably mounted on said supporting member; and spaced means projecting upwardly 65

from said supporting member for limiting the rocking movement of said rockable member.

2. In a switch control of the class described, adapted for use on a track having a 70 movable switch rail, comprising: a rockable bar; means for connecting one end of said bar to said switch rail; a movable supporting member; means for connecting the opposite end of said bar to said movable supporting member; an engagement member 75 rockably mounted on said supporting member; spaced means projecting upwardly from said supporting member for limiting the rocking movement of said rockable member; and a wedge head carried on one end of said rockable means.

3. In a switch control of the class described adapted for use on a track having a 80 movable switch rail, a rockable bar; means 85 for connecting one end of said bar to said rail; a slidably supporting member; means for connecting the opposite end of said bar to said supporting member; a wedge-shaped member 90 rockably mounted on said supporting member; and means on said supporting member for limiting rockable movement of said wedge-shaped member in either direction.

4. In a switch control of the class described adapted for use on a track having a 95 movable switch rail, a rockable bar; means for connecting one end of said bar to said rail; a slidably supporting member; means for connecting the opposite end of said bar to said supporting member; a wedge-shaped member 100 rockably mounted on said supporting member; means on said supporting member for limiting rockable movement of said wedge-shaped member in either direction; and a wedge-shaped head carried on one end of said rockable wedge member.

5. In a switch control of the class described adapted for use on a track having a 110 movably mounted switch rail, a rockably mounted bar; means for connecting one end of said bar to said rail; a slidably mounted supporting member; means for connecting the opposite end of said bar to said supporting member, the rocking of said bar effecting a movement of said switch rail from one position to another; an engagement member having inclined engaging faces at opposite sides and rockably mounted on said supporting member; and means on said supporting member for limiting rocking movement of said engagement member in either direction beyond a predetermined position.

6. In a switch control of the class described adapted for use on a track having 125 a movably mounted switch rail, a rockably mounted bar; means for connecting one end of said bar to said rail; a slidably mounted supporting member; means for connecting the opposite end of said bar to said support- 130

- ing member, the rocking of said bar effecting a movement of said switch rail from one position to another; an engagement member having inclined engaging faces at opposite 5 sides and rockably mounted on said supporting member; means on said supporting member for limiting rocking movement of said engagement member in either direction beyond a predetermined position; a separable 10 actuating member movably mounted on a vehicle travelling over said track and adapted for movement into operative and inoperative position, said separable member, upon movement of said vehicle over said track determining a predetermined line longitudinally 15 of said track and adapted for engaging one or the other of the inclined engaging surfaces of said engagement member and riding therealong, the travel of said separable member along said engaging surfaces effecting a slidable movement of said supporting member, the engagement face engaged depending upon the position of rocking 20 of said engagement member.
7. In a switch control of the class described adapted for use on a track having a movably mounted switch rail, a rockably mounted bar; means for connecting one end of said bar to said rail; a slidably mounted 25 supporting member; means for connecting the opposite end of said bar to said supporting member, the rocking of said bar effecting a movement of said switch rail from one position to another; an engagement member 30 having inclined engaging faces at opposite sides and rockably mounted on said supporting member; means on said supporting member for limiting rocking movement of said engagement member in either direction beyond a predetermined position; a separable 35 actuating member movably mounted on a vehicle travelling over said track and adapted for movement into operative and inoperative position, said separable member, upon movement of said vehicle over said track determining a predetermined line longitudinally of said track and adapted for engaging one end or the other of the inclined 40 engaging surfaces of said engagement member and riding therealong, the travel of said separable member along said engaging surfaces effecting a slidable movement of said supporting member, the engagement face engaged depending upon the position of rocking of said engagement member, the pivot 45 of said engagement member being positioned at one side or the other of said line depending upon the engagement face last engaged by said separable member; and means on said engagement member engageable with said separable member for rocking, subsequent to the slidable movement of said supporting member, said engagement member from the position to which previously 50 rocked to the extreme position of rocking in the other direction, said engagement member in either position of rocking extending across said line.
8. In a switch control of the class described adapted for use on a track having a movably mounted switch rail, a rockably mounted bar; means for connecting one end of said bar to said rail; a slidably mounted supporting member; means for connecting the opposite end of said bar to said supporting member, the rocking of said bar effecting a movement of said switch rail from one position to another; an engagement member 55 having inclined engaging faces at opposite sides and rockably mounted on said supporting member; means on said supporting member for limiting rocking movement of said engagement member in either direction beyond a predetermined position; a separable 60 actuating member movably mounted on a vehicle travelling over said track and adapted for movement into operative and inoperative position, said separable member, upon movement of said vehicle over said track determining a predetermined line longitudinally of said track and adapted for engaging one end or the other of the inclined 65 engaging surfaces of said engagement member and riding therealong, the travel of said separable member along said engaging surfaces effecting a slidable movement of said supporting member, the engagement face engaged depending upon the position of rocking of said engagement member, the pivot of said engagement member being positioned at one side or the other of said line depending upon the engagement face last engaged by said separable member; and means on said engagement member engageable with said separable member for rocking, subsequent to the slidable movement of said supporting member, said engagement member from the position to which previously 70 rocked to the extreme position of rocking in the other direction, said engagement member in either position of rocking extending across said line.
- In testimony whereof I have signed the foregoing specification.
- LOUIS BERNIER.
